UNITED STATES PATENT OFFICE.

EDMOND HOOD NEILL, OF AUSTIN, TEXAS.

MOLD CAP.

Application filed October 25, 1921. Serial No. 510,378.

To all whom it may concern:

Be it known that I, EDMOND H. NEILL, a citizen of the United States, residing at Austin, in the county of Travis and State of Texas, have invented new and useful Improvements in Mold Caps, of which the following is a specification.

My invention has reference to a casting mold for matrix setting and line casting machines, by means of which the casting slot 10 can be accurately set to given fractions or typographical measuring units.

In the accompanying drawings:

Figure 1 is a front elevation of the casting mold.

Figure 2 is a plan view looking toward the inner face of the mold cap.

Figure 3 is a plan view of the mold body.

Figure 4 is a side elevation of one of the 20 end filler blocks.

Figure 5 is an end view thereof.

Figure 6 is a view illustrating more clearly the taper at the top edge of the 25 filler block as well as the opening through which the securing screw passes.

Figure 7 is a fragmentary elevation of the mold cap, illustrating the arrangement of the slots for the quad.

Figure 8 is an end view of the mold cap 30 illustrating the beveled front edge to accommodate the screw driver in engaging lip of quad.

Figure 9 is an elevation of the quad.

Figure 10 is a view of the spacer block.

Figure 11 is a plan view thereof.

Figure 12 is a side elevation thereof.

As is well known in the art the ordinary casting mold is composed of a cap, a base, and two liners between the cap and base at 40 the ends thereof. The cap is pressed down on the liner by three screws in the mold wheel, one on each end of the cap and the other at the center. In changing the size or length of a mold, that is the length of the 45 slug the mold is set to cast, it is necessary to loosen all three of the screws, pull out the liners and replace them with others of the required size and length. For instance, say the mold is set for an 8 point slug 18 ems 50 long and it is desired to change it to a 10 point slug 13 ems in length, the liners being both 8 points, one 0 ems and the other 12 ems, and, as the length of the mold on the inside is 30 ems, this leaves the mold slot 18 ems in length and 8 points thick. To change 55 to the above measurements the three mold

cap screws are loosened and the 8 point liners are withdrawn, while a 10 point liner is arranged in one end of the mold and a 10 point liner 11 ems long is arranged in the other 60 end of the mold. The cap is then pressed down on the liners by adjusting the screws and the mold slot is 10 points thick and 13 ems long. This is comparatively an easy 65 operation if there are sufficient liners on hand, but as machines are required to set almost every measure from 4 to 30 ems on slugs of various sizes from 6 to 36 points thick, it is necessary to have in stock great 70 numbers of liners, and these become worn, bent or have an accumulation of metal 75 on them, and in such instances they will not fit perfectly so that the mold cap will not lie flat on them and the slug will be made too large or show a burr on the end and very frequently the size is affected to such an extent that it will not eject through the trimming knives.

With my improvement, the mold is constructed substantially similar to that of the 80 ordinary mold, the body 1 of the mold, at its upper edge being provided adjacent its end with the usual notch 2, and a cap 3 being provided upon its under face, adjacent its ends with a plurality of transversely arranged slots or notches 4, 5 and 6 respectively. Between the inner notches 4 the inner edge of the cap 3 is formed with transverse depressions which define straight and angular walls and which are indicated by 90 the numeral 7.

Instead of employing liners in the usual manner between the confronting faces of the body cap, at the ends thereof, I make use of filler blocks 8 respectively. These filler 95 blocks are each in the nature of a flat plate and each has its under faces formed with a lug which is designed to be received in the notch 2, the outer ends of the filler blocks being in contacting engagement with the 100 posts 10 on the ends of the body 1. The upper face of the filler block is provided with spaced notches 11 and 12 respectively, while the inner end of each filler block is provided with an upstanding lug 13, the 105 said lugs being disposed over the notch 4 in the cap 3. Each filler block has a preferably reamed opening therethrough and through this opening there is passed a headed screw 14 which enters a threaded opening 110 in the body 1.

It will be noted that the lugs 15 and 16

provided by the depressions 11 and 12 are disposed opposite the notches 5 and 6 in the cap 3, and that the notch 5 is of a less depth than the notch 6.

5 Designed to be received between the filler block and the cap 3 are quads 17 respectively. These quads may be arranged in either of the depressions 5 or 6 of the cap 3 to rest upon shoulders 15 or 16 of the filler

10 block or may be arranged in the depressions 11 and 12 of the filler block and rest on the shoulders between the depressions 4, 5 and 6 in accordance with the width desired in the casting slot, it being understood that 15 the lug 13 is never entirely withdrawn from the notch 4, and also that the notch 4 is of a greater depth than the notches 5 and 6.

It will thus be noted that the thickness 20 of the slug may be readily adjusted by the operator, and also that the operator can make such adjustment without necessitating him leaving his seat, it being merely necessary to withdraw the quad from one of its mentioned positions and reinserting the

25 same in another position. To facilitate this the outer or preferably upper corner of the quad is formed with a ledge or lip and also the quad is beveled or arranged at an inclination. In addition to this the employment 30 of the end mold cap screws may be dispensed with. The pressure from the central mold cap screw effectively holds the quads in effective engagement with the filler blocks.

35 To regulate the slot so that slugs of desired lengths can be cast I make use of what I will term spacer blocks and which are indicated in the drawings by the numeral 18. These spacer blocks are of a size to be received in the slot in the mold and as illustrated in Figure 10 of the drawings, the same may be provided with a plurality of teeth 20 to be received in the substantially V-shaped notches 7 in the inner face of the cap also, if desired, the spacer block may be provided with a single tooth. The teeth 20 of the spacer block fit snugly in the notches 7 in the mold cap, and hold the same positively in position, and of course, the space 45 between the filler block and the spacer block on the right hand side of the mold determines the length of the slot and consequently the length of the slug to be cast. To facilitate the insertion and withdrawal of the filler blocks the same are, as illustrated in the drawings substantially beveled or wedge-shaped having their inner ends rounded and their outer edges formed with lips for engagement by a suitable instrument such as a screw driver, or if desired by the fingers of the operator.

The spacer blocks, it is to be noted are of a similar construction, and are reversely arranged in position in the mold. No 60 change is made in the mold base and but

few changes are necessitated in the mold cap in providing the same with my improvement, while the element which I have referred to as a quad is really in the nature of a key which is $\frac{1}{8}$ of an inch long and 70 10 points square, with the exception of ends, one of which is provided with a lip, and the other rounded or tapered to permit the ready removal and insertion of the same.

It is also believed that the foregoing description, when taken in connection with the drawings will fully set forth the construction and advantages of the improvement to those skilled in the art to which said invention relates and that further detailed description will not be necessary. It is, or course, to be understood that I am entitled to such changes from the showing and description as may be found necessary or desirable in the manufacture thereof, such changes however, not departing from the scope of the appended claims.

Having described the invention, I claim:

1. In a line casting machine mold, the combination with a body and a cap, of filler blocks secured to the outer face of the body adjacent to the ends thereof, said blocks having their inner ends provided with lugs and said caps having notches to receive the 95 lugs and removable substantially rectangular quads between the blocks and cap for adjusting the width of the slot between said body and cap.

2. In a line casting machine mold, the combination of a body and a cap, said body and cap having their confronting faces notched and the notches in the cap varying in depth, a filler block having end ribs received respectively in the notches of the 100 body and in the inner notches of the cap, and removable substantially rectangular quads disposed between the filler block and cap for adjusting the width of the slot between the body and cap.

3. In a line casting machine mold, the combination of a body and a cap each of which having its confronting faces notched transversely and the notches in the cap varying in depth and width, of filler blocks having their ends provided with ribs which are received in the inner notches of the cap and in the notches disposed between the notches in the cap, and wedge-shaped substantially rectangular quads arranged between the notched blocks and the notched portions of the cap for adjusting the slot between the body and cap.

4. In a line casting machine mold, the combination of a body and a cap each of which having its confronting faces notched transversely and the notches in the cap varying in depth and width, of filler blocks having their ends provided with ribs which are received in the inner notches of the cap and 130

in the notches of the body respectively, said blocks having transverse notches disposed between the notches in the cap, and wedge-shaped substantially rectangular quads arranged between the notched blocks and the notched portions of the cap for adjusting the slot between the body and cap and a spacer block removably received in the slot between the blocks.

10 5. In a line casting machine mold, the combination of a body and a cap each of which having its confronting face notched transversely and the notches in the cap varying in depth and width, of filler blocks having their ends provided with ribs which are received in the inner notches of the cap and in the notches disposed between the notches in the cap, and wedge-shaped substantially rectangular quads arranged between the notched blocks and the notched portions of the cap for adjusting the slot between the body and cap, and a wedge-shaped spacer block in the slot between the blocks.

25 6. In a line casting machine mold, the combination of a body and a cap each of which having its confronting face notched transversely and the notches in the cap varying in depth and width, of filler blocks having their ends provided with ribs which are received in the inner notches of the cap and in the notches disposed between the notches in the cap, and wedge-shaped substantially rectangular quads arranged between the notched blocks and the notched portions of

the cap for adjusting the slot between the body and cap, said cap, between the blocks having transverse teeth, and spacer blocks having teeth to engage with the said teeth of the cap removably arranged in the slot 40 between the body and cap.

7. In a line casting machine mold, a body and a cap which have their confronting faces notched at the ends thereof and the notches in the cap varying in width and depth, of 45 filler blocks between the body and cap, each having inner end ribbed to be received in the inner notch of the cap and in the notch of the body, said blocks having their outer faces notched transversely and the said 50 notches being disposed between the notches in the cap, means removably securing the filler blocks to the body, substantially rectangular wedge-shaped quads having their widened ends arranged between the blocks 55 and cap for adjusting the width of the slot between the body and cap, said cap having its inner surface between the blocks provided with transverse teeth defining straight shoulders and annular walls between said 60 shoulders, wedge-shaped spacer blocks having teeth to be received between the teeth of the cap, said spacer blocks having their outer edges lipped to facilitate insertion or removal thereof, and means bearing centrally on the cap for securing the spacer blocks and quads in position.

In testimony whereof I affix my signature.

EDMOND HOOD NEILL.
